UNITED STATES PATENT OFFICE

JOHN F. REGAN, OF YOUNGSTOWN, OHIO

COKE WHARF

Application filed May 6, 1929. Serial No. 360,712.

In the manufacture of by-product coke, the coke is discharged from the ovens into suitable cars, usually of the side-dump hopper type, and carried to a quenching station where water is sprayed onto the red hot coke to partially cool it, sufficient heat being left in the coke, however, to drive off excess moisture. The cars are then routed to the coke wharf which comprises, essentially, a longitudinally extending deck downwardly inclined from its upper to its lower edge; the coke is dumped from the cars onto this deck from the car at its upper edge and allowed to remain on the deck for a length of time at least sufficient to permit it to steam, dry and cool. Owing to the inclination of the deck the coke slides down transversely thereof as it is dumped thereon, and for preventing the coke from prematurely sliding off the deck, it has therefore been customary to provide adjacent the lower edge thereof a series of vertically movable gates arranged side by side and individually manually operable through suitable operating levers from a platform parallel to the deck and upon which the operator stands when manipulating the gates. Between the lower edge of the deck and the platform in a position to receive the coke as it is discharged through the gates when the latter are lifted, a longitudinally extending conveyor is ordinarily arranged by means of which the cooled coke is conveyed to the shipping cars or other suitable point.

To permit the discharge of the cooled coke from the deck with sufficient rapidity and in sufficient volume, it has further been customary to make each gate of considerable length with the result that the gates are individually extremely heavy and therefore difficult to operate, especially as the weight of the coke pressing on the upper or inner faces of the gates enhances the difficulty of raising them, so that the men operating the gates are frequently injured through the overexertion required for their manipulation. On the other hand, if the length of the individual gates is reduced to a point at which they can be safely operated, the number of gates for a given length of wharf is correspondingly increased with resultant increase

in installation and upkeep costs as well as reduction in the amount of coke which can be discharged through each gate whereby the speed with which a given quantity of coke can be transferred from the deck to the conveyor is necessarily cut down and the time required therefor increased.

A principal object of my invention, therefore, is the provision of a coke wharf so constructed and arranged that while the discharge gates are of a size to permit them to be easily and safely manipulated, the quantity of coke which can be discharged from the deck through each gate each time that it is lifted is equal or substantially equal to that which can be discharged from a gate of twice the length when the wharf is constructed in the ordinary manner.

A further object of the invention is to provide a coke wharf so arranged that while the gates are small enough for convenient manipulation, they are capable of delivering coke to the conveyor up to its full capacity so that coke can be discharged from the deck of the wharf at maximum speed.

A still further object of the invention is to reduce the number of gates required in a given length of wharf to satisfactorily effect the discharge of the coke therefrom whereby the cost of installation of the wharf as a whole is reduced as well as the maintenance expense necessary for keeping the gates in proper operating condition.

My invention further includes other objects and novel features of design, construction and arrangement hereinafter more particularly pointed out or which will be apparent to those skilled in the art from the following description of certain embodiments of the invention as illustrated in the accompanying drawing, in which Fig. 1 is a fragmentary top plan view of a coke wharf arranged in accordance with one embodiment of the invention; Fig. 2 is a vertical transverse section through the wharf on the line 2-2 in Fig. 1 looking in the direction of the arrows; Fig. 3 is a fragmentary detail view looking toward the gates and adjacent parts in the direction indicated by the arrows on line 3-3 in Fig. 2 with the conveyor and

other parts omitted and certain portions of the gate structure being shown in section; Fig. 4 is a fragmentary top plan view illustrating a slightly modified construction and Fig. 5 a fragmentary view thereof generally conforming to Fig. 2 but with the gates and other parts omitted. The same symbols of references are used to designate the same parts in the several figures.

10 Referring now more particularly to the construction shown in Figs. 1 to 3 inclusive, the coke wharf comprises a transversely inclined deck 1 carried on a foundation generally designated as 2 of any suitable type 15 and which may also form a support for the tracks 3 on which the hopper cars may be run along the rear upper edge of the deck, which it will be understood is of indefinite length and constructed of brick or other suitable material. Adjacent the front or lower 20 edge of the deck and in a position to receive the coke as it is discharged therefrom, a longitudinally extending belt conveyor, generally designated as 4, is arranged in the usual 25 way; by means of this conveyor the cooled coke is carried to the shipping cars or other point. On the opposite side of the conveyor from that on which the deck is located is arranged an elevated longitudinally extending 30 platform or walk 5; this walk, as shown, may comprise a metal plate supported between a wall 6 and uprights 7 disposed near the edge of the conveyor and is located at a height suitable to permit convenient operation 35 of the gate handles, hereinafter described by an operator standing on the walk. The various parts to which reference has heretofore been made are commonly found in coke wharves as heretofore constructed and thus require no further or more extended 40 description; their details of arrangement and specific features of construction are a matter of choice.

45 The uprights 7 additionally form supports for brackets 10 upon which the several gates, generally designated as G, are pivotally mounted and each of which may comprise in the usual way a plate-like portion 12 which forms the gate proper and which may be 50 curved on an arc struck from the pivotal center of the gate so as to present a slightly convexed surface toward the deck; this plate-like portion is carried on a suitable frame work 13 extending toward the brackets 10 55 to which the gate as a whole is pivoted on a horizontal pivot 14. From a point adjacent the pivot an operating lever 15 is extended upward in a generally vertical direction, turned over horizontally at its upper end 60 toward the walk or platform 5 and provided at its extremity with a cross bar 16 which may be conveniently grasped by the operator; struts 17 are desirably extended between the gate frame 13 and the lever 15 so as to firmly 65 brace the structure as a whole. It will thus

be apparent that by pulling its cross bar 16 toward the walk, any gate may be swung upwardly about its pivot 14 so as to permit any coke lying on the deck 1 above or in rear of the gate and abutting against it to slide from the lower edge of the wharf onto the traveling conveyor 4.

70 More particularly from an inspection of Figs. 1 and 3, it will be noted the gates G are arranged in longitudinally spaced relation adjacent the lower edge of the deck and that between each pair of gates is disposed a baffle generally designated as B and comprising two walls 20, 21 arranged at an angle of approximately 90° to each other with the corner or edge 22 formed at the juncture of their outer faces lying midway between the adjacent gates and directed toward the upper edge of the wharf, the walls being of sufficient length to extend slightly behind the gates so that when the latter are closed, each gate forms a relatively tight fit between the adjacent baffles. As shown, the baffles are of approximately the same height as the gates and are seated on the upper face of the deck; 75 they are desirably constructed of brick or other suitable material and may be reinforced in the re-entrant angle formed between their adjacent walls and also on their ends with supports 24 formed of angle iron. It will be observed that the point or apex 80 22 of each baffle lies substantially midway between the adjacent gates and that the distance between the apices of adjacent baffles measured longitudinally of the wharf is substantially twice the width of the gate which lies between them.

85 It will thus be apparent that the adjacent baffles form a pocket in rear of, that is, above, each gate, the sides of which respectively incline toward the latter, whereby the coke as it slides down the face of the deck and encounters the baffles is deflected inwardly in 90 opposite directions toward the gate and further, that when the gate is lifted all of the coke lying on the deck in the area included in the pocket itself as well as that substantially defined by parallel lines running from the points of the adjacent baffles transversely 95 of the deck to its upper edge will pass through the gate, so that the amount of coke delivered therefrom to the conveyor will be substantially equal to the amount that would be delivered thereto by the lifting of a gate of double its length in the absence of the baffles. It will further be noted that the 100 pressure on each gate of the coke lying in the area which is drained thereby as just described and which, of course, is one of the factors contributing to the difficulty of raising the gate, is by no means as great in a coke wharf constructed in accordance with my invention as it is when a gate of the full width of a similar area is employed, for a 105 considerable amount of the weight of the 110

coke in the said area is resolved against the inclined walls of the baffles and the gate correspondingly relieved therefrom.

It is thus possible through the reduction 5 in size and weight of the gate as well as in the reduction of pressure thereon to which reference has just been made, to raise the gate relatively easily and without undue exertion, thus obviating all chance of injury 10 to the operator while, on the other hand, the relatively large area of the wharf lying above the gate can be quickly drained of coke and the conveyor thereby maintained fully loaded and at maximum operating efficiency at all 15 times.

It is customary in the operation of coke wharves to hold any given gate open until the area drained thereby is fully depleted of coke, after which that gate is closed and the 20 next gate opened. Under these conditions in the operation of coke wharves constructed in accordance with my invention, a certain amount of coke is sometimes deflected by the baffles into a pocket which has been previously 25 emptied while the adjacent pocket is being drained, with the result that this deflected coke remains in the previously emptied pocket until the gate thereof is again opened instead of passing into the adjacent pocket and being 30 drained therefrom with the rest of the coke originally in the area lying above it. To obviate this possibility and insure the draining through each gate of substantially all of the coke lying above the pocket with which 35 it communicates, a partition conveniently in the form of a metal plate 25 may be extended from the apex of each baffle toward the upper edge of the deck transversely of the latter. These partitions, as clearly shown in Figs. 4 40 and 5, may desirably be of slightly less height than the adjacent baffles and are supported in vertical position in any convenient way, for example by providing the plates 25 with feet 26 adjacent their lower edges and bolt- 45 ing or otherwise securing the feet to the deck. Under certain conditions it may be found desirable to form the partitions of brick work instead of metal plates, and while satisfactory results may usually be obtained when 50 the partitions are extended only part way across the deck as shown, they may, if desired, be carried entirely thereacross and terminated adjacent the upper edge of the deck.

55 It will thus be understood that the partitions when provided are effective to prevent any material amount of the coke which initially lies above any given pocket from being deflected into the adjacent pocket when the 60 first pocket is being drained with the result that when any given pocket is emptied it remains substantially in that condition until a new charge of coke is dumped on the deck substantially above it from one of the conveying cars running on the track 3. The de-

sirability of employing the partitions 25 will frequently be determined by the particular operating conditions encountered such as the condition of the coke when it reaches the wharf, the inclination of the latter and other like factors which will be readily appreciated by those familiar with the art.

70 While I have herein referred more particularly to the employment of my invention in connection with coke wharves provided with manually operated gates, it will be understood that the invention may be employed with equal facility in connection with those having mechanically operated gates and under such conditions will present many of 75 the advantages and desirable features to which I have herein referred, although of course the avoidance of overstrain and possible injury to the operator in raising the gates is not a factor to be considered where 80 the gates are mechanically operated.

85 While I have herein described certain embodiments of my invention with considerable particularity, I do not thereby desire or intend to specifically confine myself thereto as 90 changes and modifications may be made in the design, construction and arrangement of the various parts if desired without departing from the spirit and scope of the invention as 95 defined in the appended claims.

Having thus described my invention, I claim and desire to protect by Letters Patent of the United States:

1. A coke wharf having a longitudinally extending transversely inclined deck adapted for the reception of coke adjacent its upper edge, a plurality of longitudinally spaced vertically movable gates adjacent the lower edge of the deck, manually operable means for individually raising and lowering each of said gates, and a baffle disposed between each pair of gates and comprising walls respectively lying adjacent the ends of the gates at their lower extremities and converging upwardly and inwardly to a point of intersection located nearer the upper edge of the deck than the gates, the longitudinal distance between adjacent points of intersection being substantially twice the width of the gate included between them.

110 2. A coke wharf having a longitudinally extending transversely inclined deck adapted for the reception of coke adjacent its upper edge, a plurality of longitudinally spaced vertically movable gates adjacent the lower edge 115 of the deck, means for individually raising and lowering each of said gates, and a baffle disposed between each pair of gates and comprising walls respectively lying adjacent the ends of the gates at their lower extremities and converging upwardly and inwardly to a line substantially normal to the plane of the deck and located nearer the upper edge of the deck than the gates, the width of the baffle measured longitudinally in the plane of 120 125 130

the gates being substantially equal to the length of either gate and the distance between adjacent lines of convergence measured in the plane of the deck being substantially equal to twice the length of either gate.

5. A coke wharf comprising a longitudinally extending transversely inclined deck adapted to receive coke adjacent its upper edge, a plurality of longitudinally spaced gates disposed adjacent its lower edge and adapted to be individually raised and lowered, means for raising and lowering the gates, a V-shaped baffle disposed between each pair of gates and having its apex directed toward the upper edge of the deck, and a partition extending from the apex of the baffle toward said upper edge transversely of the deck.

4. A coke wharf comprising a longitudinally extending transversely inclined deck adapted to receive coke adjacent its upper edge, a plurality of longitudinally spaced gates disposed adjacent its lower edge adapted to be individually raised and lowered, means for manually raising and lowering the gates, a baffle disposed between each pair of gates comprising inwardly converging walls respectively extending from each gate to the apex of the baffle and disposed normal to the face of the deck, and a partition wall also normal to the face of the deck extending from the apex of the baffle toward the upper edge of the deck.

5. A coke wharf comprising a longitudinally extending transversely inclined deck, a plurality of longitudinally spaced vertically movable gates adjacent the lower edge of the deck, manually operable means for individually raising and lowering each of said gates, and a V-shaped baffle disposed between each pair of gates having its apex directed toward the upper edge of the deck and its wall disposed normal to the face thereof, the adjacent baffles being operative to form individual pockets for the reception of the coke above each gate, the maximum width of each pocket being substantially twice that of the adjacent gate.

In witness whereof, I have hereunto set
50 my hand this 30th day of April, 1929.

JOHN F. REGAN.
